UNITED STATES PATENT OFFICE.

JOSEPH N. TURNER, OF NEW YORK, N. Y., ASSIGNOR TO EBERHARD FABER PENCIL COMPANY, OF BROOKLYN, NEW YORK, A CORPORATION OF NEW YORK.

PENCIL.

1,051,033.

Specification of Letters Patent. Patented Jan. 21, 1913.

Application filed May 22, 1911. Serial No. 628,887.

To all whom it may concern:

Be it known that I, JOSEPH N. TURNER, a subject of the King of Great Britain, residing in the city of New York, county of 5 Kings, and State of New York, have invented certain new and useful Improvements in Pencils, of which the following is a specification.

This invention relates to pencils of the 10 type commonly known as "mechanical pencils", consisting of a suitable holder and means therein for moving a stick of lead in the direction of the length of the pencil.

More particularly, the invention relates 15 to pencils of this type in which means are provided for moving the stick of lead in both directions, to carry its end beyond the end of the holder to operative position or to retract it within the casing to inoperative position.

The object of the invention is to so construct a pencil of this type that it may be manufactured at very low cost, and this object is accomplished by a marked simplification of the structure, such that but a 25 small number of parts are employed, these parts may be made and assembled at very low cost, and metallic tubing of light weight may be used in making all of the required 30 parts.

The preferred embodiment of the invention is illustrated in the accompanying drawings, in which—

Figure 1 is a perspective view of the complete pencil; Fig. 2 is a perspective view of one of the parts of the casing; Fig. 3 is a perspective view of the lead-holder; Fig. 4 is a perspective view of the member within the casing coacting with the lead-holder; 40 Fig. 5 is a perspective view of the other member of the casing; and Fig. 6 is a longitudinal sectional view of the complete pencil.

Referring to these drawings, the pencil 45 consists of four tubular metallic parts, two of these parts constituting the casing of the pencil and the other two the operating members lying within the casing. The two parts constituting the casing are shown at 7 and 8

in Figs. 2 and 5, respectively. The part 50 8 is a metallic tube closed at one end and having near the other end a circumferential bead 9. The part 7 is tapered at one end as shown at 10, and at the other end of this taper is provided with two circumferential 55 beads 11 and 12. At its opposite end, the part 7 is provided with a screw-thread 13.

The lead-holder is shown at 14 in Fig. 3. It consists of a tubular metallic piece provided with a screw-thread 15 adapted to co-act with the screw-thread 13 on the part 7. The lead-holder is also provided with a lengthwise groove 16. At one end, the lead-holder is contracted to a small diameter and is split as shown at 17, so that this end may 65 be caused to grip the end of a stick of lead.

The fourth part employed in the construction of the pencil is shown at 18 in Fig. 4. It consists of a tubular metallic piece provided with a lengthwise internal projection 70 19.

In assembling the parts of the pencil, the lead-holder 14 is inserted within the part 7 of the casing by screwing it into the same, the thread 15 engaging and co-acting with 75 the thread 13 on the part 7. The part 18 is then positioned upon the threaded end of the lead-holder 14 projecting beyond the threaded end of the part 7, the internal projection 19 on the part 18 lying within the 80 lengthwise groove 16 in the lead-holder 14. The part 18 and the threaded portion of the holder 14 are of substantially the same diameter. The part 8 of the casing is then moved over the part 18 and the adjacent 85 end of the part 7, until the bead 9 thereof overlies the bead 12 on the part 7. The end of the part 8 projecting beyond the bead 9 is then contracted, so that it lies snugly upon the portion of the part 7 between the beads 11 and 12 thereof. The coaction of this contracted portion of the part 8 with the beads 11 and 12 positions the two parts 7 and 8 of the casing relatively, so that they are secured against relatively lengthwise movement but may be rotated relatively as desired. The internal 95 diameter of the part 8 of the casing is sub-

stantially the same as the external diameter of the member 18, so that this member fits snugly within casing 8. When the parts have been positioned as above indicated, a 5 portion of the casing 8 may be contracted slightly, so that it will grip the member 18 so tightly that these parts will be held rigidly together and will not rotate relatively. As thus constructed, it will be seen 10 that the pencil consists of a casing formed in two parts, which are relatively rotatable, and two members lying within the casing, one secured to one member of the casing and the other having a threaded connection with 15 the other member of the casing. These two members lying within the casing are splined together, so that they may not rotate relatively, but can move one relatively to the other in the direction of the length of the 20 pencil. Thus, by turning the part 8 of the casing relatively to the part 7, the member 18, rotating with the part 8, will cause the lead-holder 14 to turn relatively to the part 7 of the casing, and the coacting screw- 25 threads on the holder 14 and part 7 will cause the holder to move relatively to the part 7 in the direction of the length of the pencil, the spline connection between the holder and the member 18 permitting such 30 lengthwise movement. In this way, the holder 14 will be advanced or retracted as may be desired, to position the stick of lead 20 in the holder 14 for use or for protection by the casing.

35. The construction above described possesses the advantage that it provides means for moving the stick of lead positively in both directions, and when the stick of lead is worn away to a substantial extent, the 40 holder 14 may be advanced until its split end is projected through the open end of the part 7 of the casing to permit of inserting another piece of lead therein.

The construction described is one of 45 marked simplicity, permitting of the manufacture of the pencils at very low cost. It consists of but four parts, all of which may be made from metallic tubing and given the requisite form by pressing or rolling operations.

50. This simplicity results largely from the provision of a single part 14 which is provided with means for holding the stick of lead, and also with the means whereby the stick of lead is moved in the direction 55 of the length of the pencil to operative or inoperative position. The latter means consists, so far as the part 14 is concerned, of both the thread for engagement with the coacting thread on the casing and the length- 60 wise groove coacting with the projection 19 on the interior of the casing.

The construction above described and illustrated in the drawing may be modified

in various respects without departing from the spirit of the invention. For instance, 65 the invention may be employed in pens as well as in pencils, by merely modifying the shape of the end of the casing and the end of the holder 14 so that these parts will receive a suitable penpoint. Also, it is ob- 70 vious that the part 7 of the casing may be made in two parts instead of one, if that should be desirable for any reason. Thus, if it be desired to apply a lacquer to the tapered end of the casing, indicated by the 75 numeral 10, but not to the body portion of the part 7, these two portions may be separately made and thereafter secured together. In some cases, it may be desirable to make these two parts separately to avoid the application of lacquer to the body portion of the part 7, since such lacquer might ob- 80 struct the free turning movement of that part within the part 8 of the casing.

Having now described my invention, what 85 I claim as new and desire to secure by Letters Patent is as follows:

1. A pencil comprising the combination of a tubular casing of thin metal open at one end, a tubular member of thin metal 90 having one end provided with a spiral thread and projecting within the open end of the casing and having the other end tapered and projecting beyond the end of the casing, said member and casing being se- 95 cured together but capable of relative rotation, a tubular lead-holder within the casing and member provided on its exterior with a spiral thread engaging the thread on said member and with a lengthwise groove, 100 said holder having its end adjacent to the tapered end of the member formed to receive and hold a piece of lead, and a tubular piece within and secured to the casing and provided with an integral inwardly extending projection entering the lengthwise groove in the lead-holder to effect a spline between the casing and the lead-holder, sub- 105 stantially as set forth.

2. A pencil formed of four tubular pieces 110 of thin metal, one of said pieces being a casing open at one end, the second of said pieces being a member having one end provided with a spiral thread and projecting within the open end of the casing and hav- 115 ing the other end tapered and extending beyond the end of the casing, said member and casing being secured together but capable of relative rotation, the third of said pieces being a lead-holder lying within the casing and member and provided on its exterior surface with a spiral thread engaging the thread on said member and with a length- 120 wise groove, said holder having its end adjacent to the tapered end of the member 125 formed to receive and hold a piece of lead,

and the fourth one of said pieces being located within and secured to the casing and provided with an inwardly extending projection entering the lengthwise groove in the holder to effect a spline between the casing and the lead holder, substantially as set forth.

This specification signed and witnessed this 16th day of May, 1911.

JOSEPH N. TURNER.
